COMBINED STORAGE RECEPTACLE AND TISSUE HOLDER

Sherman W. Blumstein, St. Paul, Minn., assignor to
Sterling Products Co., Inc., West St. Paul, Minn.,
a corporation of Minnesota

Filed Apr. 5, 1967, Ser. No. 6,526

Term of patent 14 years

(Cl. D58—12.6)

Fig. 1

Fig. 2

Fig. 3

Fig. 4

Fig. 5

Fig. 6

Fig. 7

FIGURE 1 is a front elevational view of a combined storage receptacle and tissue holder embodying my new design;

FIGURE 2 is a side elevational view looking from the right of FIG. 1, the opposite side being a mirror image of the side shown;

FIGURE 3 is a rear elevational view;

FIGURE 4 is a top plan view;

FIGURE 5 is a bottom plan view;

FIGURE 6 is an enlarged fragmentary sectional view taken on the line 6—6 of FIG. 1; and

FIGURE 7 is an enlarged sectional view taken on the line 7—7 of FIG. 1.

I claim:

The ornamental design for a combined storage receptacle and tissue holder, as shown and described.
